UNITED STATES PATENT OFFICE.

GEORGE F. BROWN, OF HELENA, MONTANA.

BOX.

1,268,318.

Specification of Letters Patent.

Patented June 4, 1918.

Application filed August 28, 1917. Serial No. 188,617.

To all whom it may concern:

Be it known that I, GEORGE F. BROWN, a citizen of the United States, residing at Helena, in the county of Lewis and Clark 5 and State of Montana, have invented a new and useful Box, of which the following is a specification.

The present invention relates to boxes or containers, and aims to provide a novel and 10 improved box folded from a blank of paper, stiff cloth, cardboard or other suitable material, and capable of use as a suitcase or the like.

It is the object of the invention to provide 15 a box of the nature indicated which is composed of two hingedly connected parts which can be swung open and closed, and constructed in a novel manner.

A further object of the invention is the 20 provision in a box of the nature indicated, of a novel handle for carrying the box and also serving as a latch for holding the box closed, novel means being employed for assembling the handle with the parts of the 25 box.

It is also the object of the invention to provide a container of the nature indicated which can be inexpensively manufactured, and which will be thoroughly practical and 30 efficient in use.

With the foregoing and other objects in view, which will appear as the description proceeds, the invention resides in the combination and arrangement of parts and in 35 the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a perspective view of the box 45 or suitcase.

Fig. 2 is a perspective view of one corner of one part of the box.

Fig. 3 is a similar view of one corner of the other part of the box.

Fig. 4 is a cross section on the line 4—4 of Fig. 1.

Fig. 5 is a plan view of the blank from which the box is formed.

Figs. 6 and 7 are plan views of the two 55 straps of the handle.

The box comprises the opposite side walls

1 and 2 preferably of elongated or rectangular form, and having their adjacent edges connected by a bottom wall or web 3, the fold line between the bottom and side walls 60 2 serving as a hinge connection between the parts. The two parts or sections of the box are provided with the respective end walls 4 and 5 united with the ends of the side walls 1 and 2, and top walls 6 and 7 are 65 united with the edges of the side walls 1 and 2, respectively, remote from the bottom wall 3. The end, bottom and top walls extend at right angles from the side walls toward the opposite side walls of the respective parts or sections, and the ends of the top walls 6 and 7 have the flaps 8 overlapping the respective end walls 4 and 5, and provided with T-heads 9 engaged inwardly through openings 10 in said end 70 walls, to lock said tabs to the end walls, thereby holding the top and end walls in place relatively at the respective corners. The ends of the bottom wall 3 are provided with similar flaps 8' overlapping the end 80 walls 4 and provided with T-heads 9' engaging inwardly through openings 10' in said end walls, whereby the side wall 1 with its end walls 4, bottom wall 3 and top wall 6 provide the box proper, while the side 85 wall 2 and its top wall 7 and end walls 5 provide the cover hingedly connected with the bottom wall 3 to open and close the box similar to a suitcase. The flaps 8 and 8' preferably overlap the outer sides of the respective end walls, with the T-heads inserted inwardly through the openings, thereby rendering the corners of the box 90 rigid and holding them together. The box proper or body is adapted to snugly receive 95 the cover, whereby to retain the contents therein, and the end walls 4 of the body are provided at their edges with inturned flaps 11 overlapping the inner sides thereof and covering the heads 9 and 9', the end walls 100 5 of the cover fitting against the flaps 11 within the body.

In order to attach or anchor one part of the handle to the body, the upper ends of the flaps 11 have tabs 12 extending therefrom 105 underneath the top wall 6 or overlapping the inner side of said top wall and projecting toward one another. These tabs 12 have openings 13, and a handle strap 14 extends through openings 15 provided in the top 110 wall 6 near the ends thereof and between the tabs 12. The intermediate portion of the

strap 14 is on the exterior, while the terminals are on the interior and overlap the inner sides of the tabs 12, the ends of said strap extending outwardly through the 5 openings 13 and having heads 16 between said tabs and top wall 6, thereby anchoring the terminals of the handle strap 14 to the tabs 12 to prevent said strap from tearing loose. The strap 14 can slide through the 10 openings 13 and 15, whereby the strap can be moved flat against the top wall 6, the heads 16 moving toward the ends of the body, but when the intermediate portion of the strap is moved away from the top wall 6, 15 for grasping the handle by the hand, the terminals of the strap will be slid away from the ends of the body, their movement being limited by the heads 16.

The handle includes a second strap 17 having its terminals extending through 20 openings 18 in the top wall 7 of the cover, the intermediate portion of the strap 17 being outermost, and the terminals being provided at the inner side of the top wall 7 with 25 T-heads 19. This strap 17 can be moved flatly against the top wall 7, like the strap 14, and when the box is closed, the intermediate portion of the handle strap 17 can be raised through an elongated slot 20 provided 30 in the top wall 6 between the openings 15, thus bringing the strap 17 up against the strap 14, to provide a handle for conveniently lifting and carrying the box or suitcase. The two straps or parts of the handle 35 are connected to the body and cover of the box, thereby distributing the strain, and furthermore, the strap 17 in extending upwardly through the slot 20, will serve as a latch for holding the box closed, since the 40 box cannot be opened until the strap 17 is forced downwardly through the slot 20.

Having thus described the invention, what is claimed as new is:

1. A box having top and end walls, said 45 end walls having portions underlapping the top wall, and a handle strap engaging through said top wall and anchored to said portions.

2. A box having top and end walls, the 50 end walls having tabs underlapping the top wall, said top wall and tabs having open-

ings, and a handle strap inserted inwardly through the openings of the top wall and through the openings of the tabs, and provided with portions anchoring it to said 55 tabs.

3. A box having top and end walls, the end walls having tabs underlapping the top wall, the top wall and tabs having openings, and a handle strap having its terminals extending inwardly through the openings of the top wall and outwardly through the openings of the tabs, said terminals having portions between said tabs and top wall for anchoring them to said tabs. 60

4. A box embodying top and end walls, the end walls having flaps folded inwardly against the ends, said flaps having tabs underlapping the top wall, and a handle anchored to said tabs. 65

5. A box embodying top and end walls, the end walls having flaps folded inwardly against the ends, said flaps having tabs underlapping the top wall, and a handle strap having its terminals extending through the 70 top wall and tabs and anchored to said tabs. 75

6. A box embodying sections hinged together and adapted to telescope, the one into the other, top and end walls for each section, the end walls of one section having portions underlapping the top wall thereof, a handle strap passing through the top wall and anchored to said portions, the said top wall having a longitudinal slot therein, and a handle secured to the other section and 85 passing through the slot.

7. A box embodying sections hinged together and adapted for telescopic engagement, top and end walls for each section, the end walls of one section having portions underlapping the top wall thereof, a handle strap passing through the top wall and anchored to said portions, and an element secured to the other section for holding the sections in telescopic engagement. 90

In testimony that I claim the foregoing as my own, I have hereto affixed my signature in the presence of two witnesses.

GEORGE F. BROWN.
